HAND MANIPULABLE DUPLICATOR

Arthur J. Heyer, Oak Park, and Francis K. Moore,
Chicago, Ill., assignors to The Heyer Corporation,
Chicago, Ill., a corporation of Illinois

Application June 28, 1950, Serial No. 170,806

10 Claims. (Cl. 101—131)

1

This invention relates to hand manipulable duplicators adapted for printing addresses or short messages from an appropriate master carried by the duplicator. The addresses to be imprinted may be arranged in consecutive order on an elongated tape-like paper master although the device is adapted also to hold a relatively short master that bears an address or a short message. The improved duplicator is of the fluid or spirit type, that is, the masters are in reverse or mirror type or script, the typing or writing being formed on the master by use of a hectographic carbon sheet the coated surface of which is placed in contact with the side of the master opposite the side on which the address or message is initially typed or written whereby the address or message in hectographic ink, when pressed into contact with the copy sheet that has been moistened with a solvent, will provide a copy. The solvent referred to usually is an alcohol or alcohol solution.

In spirit duplicators, the fluid used in moistening the copy sheets prior to each imprinting or duplicator operation should be applied uniformly to the surface of a copy sheet if uniform reproduction is to be obtained and since the fluid evaporates rapidly and also tends to move quickly by capillary action into the body of the copy sheets, it is necessary that the imprinting operation be performed promptly after the moistening operation if use of excessive moistening fluid is to be avoided and satisfactory results are to be obtained. Where the imprinting operation can be effected immediately following the moistening operation, a minimum quantity of fluid applied to the surface of the copy sheet only is required in obtaining bright reproduction. Use of excessive fluid on the copy sheet not only is objectionable from the standpoint of economy but more ink is removed from the master at each imprinting operation where the copy sheets are unduly moistened and thus the period of usefulness of the master is reduced and its characters are likely to become smudged or blurred, thereafter producing copies that are less legible.

The principal object of the present invention, therefore, is to provide a hand manipulable duplicator provided with a moisture applying member so related to a master carrying platen that the requisite amount of fluid can be applied to the surface of a copy sheet by a stroke of the member over the sheet in one direction followed immediately by the application of the master to the moistened surface of the sheet.

Another object of the invention is to provide a

hand manipulable duplicator provided with a moistener member so located with respect to a supported master that upon completion of each moistening operation, a mere rocking or rolling action of the duplicator about the paper contacting portion of the moistener member effects application of the master to the moistened surface of the sheet thereby securing proper registration of the master with the moistened area without conscious effort or attention with respect thereto on the part of the operator and without lifting the duplicator from the copy sheet, thereby expediting the completion of the duplicating operation.

15 Another object of the invention is to provide a duplicator of the character mentioned which, in addition to providing means for carrying an elongate master provided with a relatively large number of names and addresses of customers, club members, patrons or the like which may be reproduced in succession after moving them consecutively into position upon a platen, is also provided with means for conveniently attaching a relatively short master to the platen which may bear an address, a message, shipping instructions or the like. By reason of the adaptability of the duplicator to the use of masters of the type last mentioned, the improved device, in addition to being useful in imprinting addresses on post cards, envelopes or the like is of substantial convenience in shipping rooms of factories in stamping the name and address of a consignee on multiple package shipments of merchandise, for example.

30 35 Other objects of the invention relate to various features of construction and arrangement of parts which will be apparent from the consideration of the following specification and accompanying drawings, wherein:

40 45 Figure 1 is an elevational view of a hand manipulable duplicator embodying the present improvements;

Fig. 2 is an end elevation of the duplicator;

Fig. 3 is an elevational view of the duplicator showing the side thereof not shown in Fig. 1;

45 Fig. 4 is a side elevational view of the duplicator with a hinged wall of the casing shown in raised position;

Fig. 5 is an elevational view of a moistener shown detached from the casing of the duplicator;

Fig. 6 is an enlarged sectional view taken on line 6—6 of Fig. 5;

Fig. 7 is an enlarged sectional view taken, for example, on line 7—7 of Fig. 3 and illustrating 50 55 an elongate master in position;

Fig. 8 is a similar broken sectional view illustrating a short master clamped in position on the platen;

Fig. 9 is an end elevational view of the improved duplicator in preferred position for applying moisture to a copy sheet; and

Fig. 10 is a perspective view illustrating a convenient mode of applying liquid to the moistener member.

In the drawing, the duplicator is shown as comprising a casing preferably formed of sheet metal and comprising end walls 10 and 11, a relatively fixed side wall 12 secured, as by spot welding, to the walls 10 and 11 and a hinged wall 13 which enables the same to be swung to the open position as shown in Fig. 4. When in closed position, ears 14 at opposite sides of the wall 13 retain the same in closed position by snap action. In Fig. 4, the casing is shown as provided with a pair of spools 15 and 16 removably mounted upon drive spindles 17, 17 that are rotatable manually by means of knobs 18. The knob operable spindles 17 are provided with opposed lugs 19 which engage in transverse slots in the ends of the hollow spools whereby when either knob is rotated, the corresponding spool likewise will be rotated. The opposite ends of the spools are carried on spindles 20, 20 and contact springs 21 surrounding the respective spindles whereby the springs act as brakes tending to hold the spools against inadvertent rotation and loss of tension placed upon a master tape carried by the spools. The inner ends of the wires forming the springs 21 are shown as being connected together by a small rubber tube 22 for convenience of assembly. Either spool can be removed from the casing readily by shifting it to the left as viewed in Fig. 4, against the action of the respective spring for freeing the opposite end from the spindle 17. Both ends of the spools are provided with cross slots for receiving the drive lugs 19 and hence the spools can be placed in position with either of the ends on the respective drive spindle 17.

The lower ends of the end walls 10 and 11 carry a platen 23 the lower surface of which is convex as shown in Fig. 8. The platen is secured to the end walls by any appropriate means such as screws 24. The side walls 12 and 13 are shown as terminating above the adjacent longitudinal edges of the platen 23 to provide openings through which an elongate master 25, as shown in Fig. 5, may pass from one spool into contact with the exterior curved surface of the platen and thence into the casing to the other spool. Located adjacent the longitudinal edges of the platen 23 are rollers 26 which are attached to the respective end walls 10 and 11 by pivots 27. The master 25 contacts the rollers as shown in Fig. 7 which avoid the formation of sharp bends in the master at the edges of the platen and facilitates the advancement of the master over the curved surface of the platen.

The master 25 preferably is of paper and is adapted to have names and addresses typed or written thereon in reverse or mirror characters in duplicating ink. The successive addresses should be spaced a short distance apart, as for example, two or three typewriter spaces. Viewing Fig. 7, it will be seen that by rotating one of the knobs 18 in a direction to wind up the master, it can be drawn across the exterior convex face of the platen 23 for effecting location of a name and address on the platen in duplicating position. The master preferably is of a

length adapting it to carry a relatively large number of names and addresses which, by operating one knob or the other, may be advanced consecutively, if desired, to duplicating position on the platen whereby a large number of cards, envelopes or the like may be addressed rapidly in succession.

The duplicator is provided with a moistening device adapted to apply moisture to the surface of the copy sheet which may be a card, envelope, or the like prior to the imprinting or duplicating operation. The preferred form of the moistening device is shown in Figs. 5 and 6 and, as will be seen, comprises a holder or cartridge indicated generally by the numeral 28 for holding a felt wick or the like 29. As shown in Figs. 5 and 6, the cartridge is formed of a pair of sheet metal plates 30 and 31 which may be fastened together in spaced apart relation by ears 32 with the wick 29 clamped between the plates. At the lower end, the plate 30 is directed to the right as viewed in Fig. 6 at approximately 45° to form a lip 33. The upper end of the member 30 extends above the corresponding end of member 31 whereby there is provided a transverse opening 34 in the upper end of the cartridge into which fluid may be poured as from a suitable container 35 as shown in Fig. 10. The lower end of the wick 29 which is shown as being formed of two thicknesses of felt projects beyond the lip 33 to provide a copy sheet contacting portion which applies moisture to the copy sheet during the moistening operation. The plate 31 of the cartridge is provided with an undercut stud 36 and also a knurled nut 37 carried by a screw 38 which is secured to the casing wall 31. Stud 36 and clamp nut 37 are arranged in the vertical center line of the wall 31 and are adapted to be received within an open slot 39 provided in the casing wall 12. As viewed in Fig. 7, it will be seen that the moistener cartridge can be slid upwardly into the interior of the casing to cause a lower stop flange 40 to engage the lower edge of the wall 12 and that upon tightening the nut 37, the moistener will be retained in the properly aligned position illustrated in Fig. 7, in which the exposed end of the wick 29 is parallel with the platen 23. The cartridge can readily be removed for supplying liquid to the cartridge when desired.

Assuming that the operator has adjusted the master 25 to position a selected address over the platen 23 and that the wick has been suitably supplied with fluid, he can hold the duplicator in one hand, position it as indicated in Fig. 9 with the end portion of the wick 29 upon a copy sheet 41 which should rest upon a suitable, smooth support and draw it toward him or to the right as viewed in Fig. 9 to apply moisture to an adequate area of the copy sheet, whereupon, without lifting the duplicator from the sheet, he can roll it or tilt it in the opposite direction about the lower end of the moistener as a fulcrum to cause the platen to roll the working portion of the master into contact with the moistened portion of the copy sheet. It will be seen that the duplicating operation can quickly be performed by merely drawing the duplicator while in the tilted position of Fig. 9 toward the operator and then rolling it upon the platen in the opposite direction. This arrangement avoids any conscious effort on the part of the operator to procure registration of the master portion on the platen with the moistened surface of the copy sheet and proper alignment of the imprinted

matter on the copy sheet can readily be obtained.

The projecting end of the moistener wick 29 spaces the duplicator sufficiently above the copy sheet during moistening operations as to avoid contact of the master with the copy sheet during the moistening operation, thus protecting the master against smudging and smearing which would occur should the characters on the master be drawn into contact with the moistened surface of the copy sheet. The exposed end portion of the wick is held in a laterally off-set relation with respect to the adjacent wall 12 of the casing and terminates in a plane that is substantially tangent to the adjacent longitudinal edge of the curved face of the platen and hence as the duplicator is rocked counter-clockwise from the moistening position shown in Fig. 9, the adjacent edge of the convex face of the platen will be brought into contact with the copy sheet whereby the entire convex face of the platen can roll on the copy sheet in pressing the master into uniform contact with the moistened area. Since the moistening and imprinting operations can be performed in rapid succession, a minimum quantity of fluid need be applied to the surface of the copy sheet, thus economizing on the use of the fluid and, since the imprinting operation can be effected immediately following the moistening operation without moving the duplicator from the copy sheet, the imprinting operation can be accomplished before any substantial evaporation of the fluid from the copy sheet has occurred or before substantial portions of the applied liquid has had time to pass into the copy sheet by capillary action.

For the purpose of enabling the duplicator to be used in the manner of a hand stamp for imprinting a particular address or message a number of times that does not appear on an elongated master, means are provided for adapting the duplicator to the use of relatively short masters such as is indicated at 42 in Fig. 8. Such a short master may be prepared in a manner similar to that above described and, as will be seen, extends across the curved surface of the platen 23 and has one end anchored by a clamp member 43 and the other end secured by a wire clamping member 44 which is carried by the hinged casing member 13. The clamp 43 is located above the platen and is pivotally secured to the end plates 12 and 13 by means of pivot members 45 which project through openings provided in the plates 10 and 11. Springs 46 encircle the pivotal projections 45 within the casing, one end of each of which bears against the upper surface of the clamp 43 while the opposite ends of the springs extend into contact with suitable supports such as the journals for the spindles of the lower spool, as shown in the particular construction illustrated.

A stop or margin bar is provided for cooperation with the clamp 43 for arresting inward movement of an end portion of a short master 42 in proper position. In the structure illustrated, a margin bar 47 is shown as formed integrally with the upper face of the platen member and against which an end of a short master is adapted to be placed in abutting contact when the clamp 43 has been raised manually by means of a finger piece 48 that projects through a slot 49 in the end wall 10. Release of the finger piece permits the clamp to engage the inserted master adjacent the end thereof after which the master can be drawn across the convex face of the platen and secured at the other end by a clamp 44 se-

cured to the hinge wall 13. A spring 50 (see Fig. 4) presses the transverse portion 44a of the bail like clamp into contact with the lower edge portion of the wall 13 and permit the clamp to be moved away from the wall for insertion of the end of the master into clamped relation on a master as shown in Fig. 8. The master 42 should have the copyable matter so arranged thereon as to be disposed between the longitudinal edges of the platen when the master is in use whereby the copies can be made by applying liquid to the copy sheet, whether it be a shipping label, tag, package, or other article, and then by rolling the master into contact with the moistened area as above described. A short master 42 may be used to advantage in shipping rooms for directing a number of packages to the same consignee, as a substitute for a rubber stamp, but with the advantage that such a master can be made in a few seconds' time at practically no cost and can be saved, if desired, for re-use since a properly made master of the type under consideration will usually provide over a hundred legible copies. Where a shipping clerk has available a number of such masters bearing names and addresses of regular customers, it requires but a few seconds' time to place a master in position on the duplicator for imprinting the address on the packages constituting a shipment, as mentioned above.

The foregoing description of the improvements are believed sufficient to give a clear understanding of the structure of the duplicator and of some of its uses. The location of the liquid applying portion of the moistener, with respect to the platen, as described and illustrated, is important since an operator by a simple wiping action of the moistener along the copy sheet in one direction can moisten an area at least as wide as the master and by merely rocking the duplicator in the opposite direction can move the master on the platen into contact with the moistened area in making the copy. Use of one hand only is required in the moistening and imprinting operations which leaves the other hand free for handling the copy sheets.

45 While a preferred form of the hand manipulable duplicator has been shown and described for illustrative purposes, various changes in the details of construction may be made within the scope of the invention defined by the following claims.

We claim:

1. A hand manipulable duplicator of the spirit type comprising a casing provided with end walls, a platen provided with a convex lower surface secured to the lower ends of said end walls and upon which the duplicator can be rocked manually in pressing the portion of a master thereon into rolling contact with a copy sheet, said casing being provided with side walls having openings therein along the longitudinal edges of the platen through which the opposed ends of the said master on the platen may pass to the interior of the casing, means within the casing for engaging said ends for maintaining the master in taut relation with respect to the platen, and a copy sheet moistening member projecting at the lower portion thereof through one of said openings and terminating at the lower end parallel with and spaced laterally from the adjacent convex portion of the platen and at an elevation above the same when the duplicator is in a vertical position whereby when the duplicator has been tilted from said vertical position to an inclined position wherein the said end of the moistener member is lowermost the said

end of the moistening member provides a support for the duplicator that spaces the platen and the portion of the master thereon above the copy sheet as the duplicator is moved in said inclined position parallel with the copy sheet for applying moisture to the same.

2. A hand manipulable duplicator of the spirit type comprising a casing provided with end walls, a platen provided with a convex lower surface secured to the lower ends of said end walls and upon which the duplicator can be rocked manually in pressing the portion of a master thereon into rolling contact with a copy sheet, said casing being provided with side walls having openings along the longitudinal edges of the platen through which the opposed ends of the said master on the platen may pass to the interior of the casing, means within the casing for engaging said ends for maintaining the master in taut relation with respect to the platen, and a moistener member secured to a side of the casing and provided with a copy sheet contactable portion disposed parallel with the platen and located at an elevation above the same when the duplicator is in an upright position and projecting laterally from the casing a distance to space the platen from an adjacent copy sheet as the duplicator in tilted relation is drawn over a copy sheet with said portion of the moistener in contact with the copy sheet during a moistening operation.

3. A hand manipulable duplicator of the spirit type comprising a casing provided with end walls, a platen provided with a convex lower surface secured to the lower ends of said end walls and upon which the duplicator can be rocked manually in pressing the portion of a master thereon into rolling contact with a copy sheet, said casing being provided with side walls terminating above said platen to provide openings through which the opposed ends of the said master on the platen may pass to the interior of the casing, means within the casing for engaging said ends for maintaining the master in taut relation with respect to the platen, and a moistener member mounted upon said casing for applying liquid to a copy sheet comprising a copy sheet contactable portion located at an elevation above said platen and extending laterally of the casing a distance whereby tilting of the duplicator in one direction to an angle of approximately 45 degrees with respect to a subjacent copy sheet moves said portion of the said moistener member into contact with the copy sheet and elevates the platen above the copy sheet and enables the moistener member to apply moisture to the sheet as the duplicator is moved in a direction parallel with the copy sheet and from which tilted position the duplicator can be rocked in the opposite direction to cause the platen to move into engagement with the moistened area of the copy sheet and to press said contacting portion of the master into printing relation with said moistened area of the copy sheet.

4. A hand manipulable duplicator comprising a casing provided with end walls, a platen disposed between and secured to the lower ends of said end walls and provided with a convex lower surface, said casing being provided with front and rear walls terminating above the platen to provide openings for the passing into and egress from the casing of an elongate master extending over the convex surface of the platen, rotatable spools in the casing upon which the portions of the master extending into the casing

are adapted to be wound, and a copy sheet moistener member removably secured within the casing and provided with a copy sheet contacting portion extending through one of said openings to the exterior of the casing and extending laterally to a position whereby the duplicator can be tilted to a position to cause said end portion of the moistener member to contact a subjacent copy sheet while the platen is elevated above the copy sheet for avoiding contact of the master with the moistened area of the copy sheet formed by moving the duplicator in said inclined position with said end of the moistener member in contact with the copy sheet.

5. A hand manipulable duplicator comprising a casing provided with end walls, a platen extending transversely between the lower ends of said end walls and secured thereto, said platen being provided with a convex lower surface, said casing being provided with front and rear walls provided with openings above the platen for accommodating portions of an elongate master passing over said convex surface of the platen to the interior of the casing, and a moistener member in the casing comprising a wick the lower portion of which extends outwardly of the casing through one of said openings and terminates in a copy sheet contacting end adapted for wiping contact with a subjacent copy sheet for applying moisture thereto as the duplicator, in tilted relation, is moved over the copy sheet.

6. A hand manipulable duplicator comprising a casing provided with end walls, a platen extending transversely between the lower ends of said end walls and secured thereto, said platen being provided with a convex lower surface, said casing being provided with front and rear walls provided with openings above the platen for accommodating portions of an elongate master passing over said convex surface of the platen to the interior of the casing, and a moistener member within the casing comprising a wick the lower end portion of which extends outwardly of the casing through one of said openings, and an angularly disposed backing member for said portion of the wick for holding the same in a position wherein said portion extends laterally beyond the plane of the adjacent wall to enable the lower end of said portion to be drawn in wiping contact with a subjacent copy sheet for applying moisture thereto.

7. A hand manipulable duplicator comprising a casing provided with end walls, a platen disposed between the lower ends of said end walls and provided with a lower convex surface across which a master is adapted to extend, means for retaining a master in taut relation over said convex surface of the platen for rolling contact with a moistened surface of the copy sheet, and a moistener member carried by the casing and provided with an end portion for applying the fluid to a copy sheet by wiping contact therewith, said end portion of the moistener being of a width not less than the width of the copyable matter on the master and located at an elevation above the platen and disposed in parallel, laterally offset relation with respect to the platen whereby upon moving the duplicator in one direction across a copy sheet with said end portion of the moistener member in contact with a subjacent copy sheet for moistening the same said end portion of the moistener member constitutes a supporting fulcrum about which the duplicator can be rocked to move the portion of the master on the adjacent longitudinal edge of the convex

surface of the platen into contact with the moistened area of the copy sheet.

8. A hand manipulable duplicator comprising a casing provided with a platen at the lower end thereof, said platen having a convex surface over which a master is adapted to be held and pressed into rolling contact with a moistened area of a copy sheet by manual rocking action of the duplicator upon the platen, means for securing a master in contact with said convex surface of the platen, a moistener for applying liquid to the copy sheet comprising a wick holder secured to the casing and a wick member extending from the holder and provided with a copy sheet contacting end arranged parallel with the platen and disposed at an elevation above and laterally thereof whereby with the duplicator tilted in one direction to rest upon the wick end and moved in such tilted position along a copy sheet an area thereof can be moistened with which the master upon the platen will register upon tilting movement of the platen in the opposite direction.

9. A hand manipulable duplicator comprising a casing provided with a platen at the lower end having a convex lower surface over which a master can be held and pressed into rolling contact with a moistened area of a copy sheet by manual rocking movement of the duplicator upon the platen, means for attaching a master in position over said convex surface of the platen, and a moistening member having a copy sheet contacting portion disposed parallel with the platen at one side thereof and disposed in a plane substantially tangent to the adjacent longitudinal edge portion of the convex surface of the platen.

10. In a hand manipulable spirit duplicator, a casing constituting a hand grip by means of which the duplicator can be manipulated, said casing being provided with a platen having a con-

vex surface at the lower end for supporting a working portion of a master in duplicating position, means for securing a master in duplicating position on said convex surface, the casing being provided with a transverse opening at one side thereof above the platen, and a moistening member removably mounted within the casing and comprising a wick and a supporting cartridge therefor removable through said opening, said cartridge being provided with a pair of wall members clamping the major portion of the wick therebetween, one end of said wick extending outwardly from the lower end of the cartridge and projecting through said opening in the casing to a position laterally of the casing to enable said end of the wick to be held in moistening contact with a copy sheet as the duplicator is moved over the sheet in a position of inclination wherein the platen is elevated from the sheet.

ARTHUR J. HEYER.
